UNITED STATES PATENT OFFICE.

WILLIAM H. WINSLOW, OF CHICAGO, ILLINOIS.

DESIGN FOR A PRISM-LIGHT.

SPECIFICATION forming part of Design No. 26,890, dated April 12, 1897.

Application filed February 9, 1897. Serial No. 622,674. Term of patent 14 years.

To all whom it may concern:

Be it known that I, WILLIAM H. WINSLOW, a citizen of the United States, residing at Chicago, in the county of Cook and State of Illinois, have invented a certain new and useful Design for Ornamental Prism-Lights, of which the following is a description.

My invention relates to a new and improved design for a prism-light and is illustrated in the accompanying drawings, wherein—

Figure 1 shows a perspective view of a prism-light embodying my invention, and Fig. 2 a section.

Like letters refer to like parts throughout both views.

The design consists of the prism-light A, provided at one side with the series of sub-

stantially parallel prisms B B, separated by grooves or indentations C C and having plane sides. These prisms extend completely across the face of the light, as shown.

The essential feature is the prism-light provided on one side with the substantially parallel projecting prisms having plane surfaces and extending substantially across the face of the light, as shown.

I claim—

The design for a prism-light as herein shown and described.

WILLIAM H. WINSLOW.
